JOHN BERCHMANS WELCH, OF NEW ORLEANS, LOUISIANA.

APPARATUS FOR DRYING WOOD, LUMBER, AND THE LIKE.

Application filed September 30, 1924. Serial No. 740,708.

This invention relates to the art of drying materials such as lumber, wood, or the like, and has for its object the provision of an improved apparatus for drying such materials. More particularly, the invention aims to provide an apparatus for drying materials such as lumber or wood, in which the temperature and humidity of the drying medium are automatically controlled in response to changes in a varying characteristic (such as weight or moisture content) of the material undergoing drying as the drying progresses.

The invention relates especially to the drying of lumber or wood, and will be described throughout this specification as applied to that industry. It is to be understood, however, that the principles of the invention are applicable to the drying of other materials where different conditions of temperature and humidity are required in the course of the drying operation.

The controlling factors in the drying of lumber, and of wood generally, are the moisture content of the wood, the thickness of the wood, and the species. Woods which are easily subject to splitting in drying must be treated at a low temperature and a high humidity. If the wood has a high percentage of moisture the starting temperature must be lower and the humidity higher than if the same wood had been air-dried down to a low moisture content before being put in the drying kiln. In other words, the moisture content of the wood is the controlling factor for any particular thickness and species.

In the careful drying of wood, the moisture content of the wood is first determined and the appropriate temperature and humidity of the drying medium for that moisture content are thereby established. After the wood has been dried down to a lower moisture content, more severe conditions of temperature and humidity of the drying medium are allowable. Heretofore, in the careful drying of wood, it has been necessary for the operator to periodically go into the kiln, take a sample of the wood undergoing drying, and make a moisture determination of that sample in order to find out if the moisture content is low enough to permit or warrant a new setting of the conditions of temperature and humidity. In practice, this necessitates daily weighing of samples from each kiln to determine the appropriate

conditions for the drying operation. Often, even in the hands of a skillful operator, the drying proceeds too far before conditions are changed, and then again conditions are sometimes changed before the lumber or wood is dry enough to stand the altered conditions of temperature and humidity.

The high temperatures and humidity within a lumber drying kiln make the duty of entering the kiln for obtaining samples most arduous, and on this account, the drying is seldom controlled by the moisture content of the wood as it should be, but is more often based on a time schedule. This schedule is set after the moisture content of the wood is determined and before drying commences. If everything proceeds without interruption, good drying may be accomplished. However, any interruptions in the drying, such as low steam pressure, shutting down of the kilns or boilers for repairs, changes in weather conditions which affect the temperature within the kiln, and a variety of other causes, often slow up the actual drying so that the lumber or wood is not able to stand the increasing temperature and decreasing humidity called for by the drying schedule. As a result, there is often a considerable loss of lumber due to splitting caused by too rapid drying.

The present invention contemplates an improved apparatus for drying materials, such as wood or lumber, in which the material itself, according to its weight or moisture content, from within the drying kiln, automatically prescribes the appropriate temperature and humidity conditions which are required throughout the entire drying operation. Thus, the invention involves the provision of certain expedients for controlling and adjusting the conditions of temperature and humidity of the drying medium in response to the decreasing moisture content of the material undergoing drying. In accordance with the invention any standard temperature and humidity controller may be automatically set and adjusted to control the conditions of temperature and humidity of the drying medium as prescribed by changes in the weight or moisture content of the material undergoing drying.

In general, the invention contemplates the provision, in conjunction with a temperature or humidity, or a temperature and humidity controller having temperature setting means cooperating with means for main-

taining the temperature substantially uniform and humidity setting means cooperating with means for maintaining the humidity substantially uniform, of an electromagnet, means for adjusting temperature or humidity, or the temperature and humidity setting means actuated by the electromagnet, means for producing an action indicative of the loss of weight of a representative sample of the material being dried as the drying operation progresses, and means for actuating the electromagnet in response to said action.

The novel features of the invention will be more clearly understood from the following description taken in conjunction with the accompanying drawings which diagrammatically illustrate the various features of the invention, in which;

20 Fig. 1 is a diagrammatic view of a complete setup;

Fig. 2 is a diagrammatic view of parts of Fig. 1 on a large scale;

25 Fig. 3 is a sectional view on the line 3—3 of Fig. 2; and

Fig. 4 is a diagrammatic perspective view of a temperature helical coil (which is similar to the humidity helical coil described below).

30 In the drawings I have illustrated temperature and humidity controllers combined in a single case and comprising a frame or body 1 having pivoted thereon a temperature-setting means or pointer 2 and a humidity-setting means or pointer 3, which are set or adjusted to their appropriate positions in a manner which will be hereinafter described. A temperature-indicating pointer 4 and a humidity-indicating pointer 5 are mounted upon the body or frame 1 in operative association with the temperature-setting means 2 and the humidity-setting means 3 respectively. The temperature-indicating pointer 4 is actuated by a temperature element or dry bulb 6. The temperature element or dry bulb 6 is of the usual type, containing a volatile liquid or gas which, when subjected to heat, becomes volatilized and the vapor pressure is transmitted 45 through a flexible tube 7 to a helical coil 8. The movement of the helical coil 8 is transmitted to the temperature-indicating pointer 4 by means of links 9 and 10. The humidity-indicating pointer 5 is actuated in like manner by the wet bulb 11 through the flexible tube 12, helical coil 13, and links 14 and 15.

50 A duplex valve mechanism is mounted upon the body or frame 1 of the temperature and humidity controllers and comprises a temperature control valve having a valve chamber 16 which communicates by a passage 17 with a compressed air supply pipe 18. The valve chamber 16 contains a valve head 19 adapted to open or close a port 20 to the atmosphere and simultaneously to

close or open (respectively) the passage 17. The valve-head 19 is carried by a hollow valve stem 21 providing communication between the valve chamber 16 and a bellows diaphragm 22. The diaphragm 22 communicates by a flexible tubing 23 with an air nozzle 24 mounted upon the temperature-setting means or pointer 2. A flapper valve 25 is mounted upon the temperature-indicating pointer 4 so as to close the air nozzle 24 as the temperature-indicating pointer moves into a predetermined position with respect to the temperature-setting pointer 2. An air pipe 26 provides communication between the valve chamber 16 and an air-operated steam valve 27 which controls the supply of steam to the kiln.

The humidity control valve is of similar construction to the temperature control valve and comprises a valve chamber 28 having a passage 29 connected to the air supply pipe 18. A valve head 30 is adapted to open or close a port 31 to the atmosphere and simultaneously to close or open (respectively) the passage 29. The valve head 30 is mounted on a hollow valve stem 32 communicating between the valve chamber 28 and a bellows diaphragm 33. The diaphragm 33, attached to frame 1 in any appropriate manner (not shown), communicates by a flexible tubing 34 with an air nozzle 35 mounted on the humidity-setting pointer 3. A flapper valve 36 is mounted on the humidity-indicating pointer 5 to close the air nozzle 35 as the humidity-indicating pointer 5 approaches within a predetermined distance of the humidity-setting pointer 3. An air pipe 37 communicates between the valve chamber 28 and an air operated spray valve 38, operating the spray within the kiln. The air pipe 37 also communicates with a damper valve 39 for opening or closing a damper 40 in the kiln.

The air lines 18, 26 and 37 are provided with pressure gauges 90 to indicate the air pressure in these lines.

As is shown in the drawings, when the valve head 19 closes the port 20 and opens the passage 17, the air supply pipe 18 is in direct communication with the air pipe 26, thereby permitting compressed air to pass into the pipe 26 and open the steam valve 27, whereupon steam enters the heating pipes within the kiln. So long as the temperature within the kiln remains lower than the predetermined prescribed temperature, the valve 27 will remain open. As the temperature within the kiln rises, the temperature-indicating pointer 4 moves towards the temperature-setting pointer 2 until the temperature within the kiln reaches the prescribed temperature, whereupon the flapper valve 25 engages and closes the air nozzle 24. This causes the air pressure to be thrown back into the bellows diaphragm 22 which thereupon expands

and moves the valve head 19 to close the passage 17, thereby permitting the compressed air in the pipe 26 and valve 27 to escape to the atmosphere through the port 20 in the valve chamber 16. The valve 27 thereupon closes and shuts off the steam supply to the kiln. When the temperature within the kiln has again fallen to below the prescribed temperature, the temperature indicating pointer 4 will move away from the temperature-setting pointer 2, causing disengagement between the air nozzle 24 and the flapper valve 25. The diaphragm 22 will then contract and permit the valve 19 to return to its original position and the steam valve 27 will again open. In a similar manner, if the humidity within the kiln rises above the predetermined prescribed condition, the humidity-indicating pointer 5 will move towards the humidity-setting pointer 3 to cause the flapper valve 36 to close the air nozzle 35 to appropriately operate the spray valve 38 and the damper valve 39.

As the drying operation progresses, the moisture content of the material being dried becomes lower, permitting more severe temperature and humidity conditions. It is, therefore, necessary at various intervals to adjust or move the temperature-setting pointer 2, and the humidity-setting pointer 3 to new positions, as prescribed by the loss in weight or moisture content of the material being dried. For this purpose I provide certain novel features for automatically adjusting the position of the temperature-setting pointer 2 and the humidity setting pointer 3 to new positions, as prescribed by the loss in weight or moisture content of the material being dried. For this purpose I provide certain novel features for automatically adjusting the positions of the temperature-setting pointer 2 and the humidity-setting pointer 3 in response to the loss in weight of a representative sample of the material being dried.

The control sample 41 is a representative sample of the wood to be dried and may conveniently be approximately 8 inches wide and 24 inches long. This sample is placed on a special type of scales within the kiln. The sample is preferably so positioned that the action thereon of the drying medium within the kiln is fairly representative of the action of that medium throughout the kiln. The sample 41 is carried by a pair of depending gripping hooks 42 pivotally mounted near one end of a horizontally positioned balance arm 43. The balance arm is operatively supported by a pair of stationary knife edges 44 cooperating with notches near the other end of the arm and by a knife edge support 45 cooperating with knife edges 46 above the arm and intermediate its ends but relatively nearer the end cooperating with the knife edges 44. The knife edges

46 are secured to a tube 47. A flexible strap 48 is secured at one end to the tube 47, which, passing over the top of the tube, is fastened at the other or depending end to the balance arm 43. A depending rod 49 is secured to the tube 47 and carries a counter-balance weight 50.

The stationary knife edges 44 and the knife edge support 45 may conveniently be mounted on a portable panel 51. This panel 75 may also advantageously carry the electrical controlling switch or other device of the instrumentalities for transmitting movements of the balance arm 43 to a desired point outside the kiln. The electrical controlling switch comprises a series of contacts 52 electrically connected to one terminal of an electromagnet or relay winding 53, and a second series of contacts 54 electrically connected to one terminal of an electromagnet or relay winding 55. The other terminals of the windings 53 and 55 are electrically connected to a movable contact 56 actuated by the scales arm 43 through the rod 49 and a connecting member 57. A battery 58 is in the common circuit connection between the contact 56 and the windings 53 and 55.

An armature piston 59 is operatively arranged to be moved towards the left when the relay winding 53 is energized and towards the right when the relay winding 55 is energized. The piston 59 carries a pin 60 engaging in a slot in a rocker cam 61 so that when the winding 53 is energized the cam is turned counter-clockwise, and when the winding 55 is energized the cam is turned clockwise. A spring 62 mechanically connects the cam 61 with a movable switch arm 63 adapted to engage with either of two spring contacts 64 and 65. The cam 61 is electrically connected to the movable switch arm 63 through the metallic frame of the instrument or through the spring 62.

The cam 61 carries two lugs 66 and 67 adapted to engage with and lock the switch contacts 64 and 65 respectively in such a manner that the piston 59 can move almost its completed distance towards the winding 53 (or the winding 55) before the spring 62 will act to throw the arm 63 from engagement with the contact 64 into engagement with the contact 65, or vice-versa.

The piston 59 carries a flexible contact 68 arranged to have a sweeping engagement with a stationary contact 69 as the piston is moved in response to the energization of first one and then the other of the windings 53 and 55. The contacts 68 and 69 are included in an electrical circuit with a battery 70 and an electromagnet or relay winding 71.

An armature plunger 72 is operatively mounted with respect to the winding 71. At its upper or inner end the armature 72

is pivotally connected to a lever arm 73 which in turn is pivotally mounted on a shaft or spindle 74. A spring 75 normally holds the lever arm 73 in the position as shown in the drawings. The lever arm 73 carries a spring-pressed pawl 76 cooperating with a ratchet 77 secured to the shaft or spindle 74. Setting screws 78 are provided for determining the movement of the armature 72 each time the winding 71 is energized. Adjustment of the screws 78 permits adjustment of the number of teeth of the ratchet 77 moved each time the winding 71 is energized.

15 The ratchet 77 is always moved in the same direction by the armature 72. A temperature-adjusting cam 79 and a humidity-adjusting cam 80 are also secured to the shaft 74. Movement of the temperature-adjusting cam 79 actuates a cam lever arm 81 formed by one arm of a bell crank 82 loosely mounted on a shaft or spindle 83. The other arm of the bell crank 82 is connected by a link 84 to the temperature-setting means or pointer 2. The cam lever arm 81 is held in contact with the temperature-adjusting cam 79 by means of a spring 85.

Movement of the humidity-adjusting cam 80 actuates a cam lever arm 86 forming one arm of a bell crank 87 which is also loosely mounted on the shaft or spindle 83. The bell crank 87 is connected to the humidity-setting means or pointer 3 by means of a link 88 and is held against the cam 80 by a spring 85.

In the drawings, I have shown a construction of scale switch which I prefer to employ in conjunction with the equipment illustrated.

40 The contacts 52 are carried in the top segment of a ring of insulating material 89, preferably made of bakelite. The contacts 54 are carried on the bottom segment of the ring 89. The movable contact 56 (connected to the link 57) is arranged to alternately engage with the contacts 52 and 54.

45 As the moisture content dries from the sample 41, the arm or rod 49 moves toward a vertical position, and this movement is so transmitted to the contact 56 that the contacts 52 and 54 are alternately engaged. In the position as shown in the drawings, the contact 56 is in engagement with one of the contacts 52. This causes the energization of 50 the electromagnet 53 and movement of the movable element or plunger 59. As the plunger 59 moves toward the left, as shown in the drawings, in response to the energization of the electromagnet 53, the movable contact 68 sweeps past the stationary contact 69 to close the circuit through the battery 70 and winding 71. At the same time the cam 61 is forced to the left by the pin 60 carried by the plunger 59, causing the 65 spring 62 to move the switch arm 63 from

engagement with the contact 65 and into engagement with the contact 64, thus de-energizing the windings of the electromagnet 53. When the electromagnetic device 71 is energized, its plunger 72 is drawn down, causing a movement of the lever arm 73 with the resulting movement of the ratchet 77 a predetermined prescribed amount. The movement of the ratchet 77 causes the movement of the temperature-adjusting cam 79 and humidity-adjusting cam 80 a predetermined prescribed amount. In this manner the temperature-setting pointer 2 is moved a predetermined prescribed amount by means of cam lever arm 81, bell crank 82, and link 84. Likewise, the humidity-setting pointer 3 is moved a pre-determined prescribed amount by the operation of the cam lever arm 86, bell crank 87, and link 88. It will be noted that the windings of the electromagnetic device 71 are energized only momentarily while the movable contact 68 is sweeping past the stationary contact 69.

As the moisture content of the sample 41 becomes further reduced, the movable contact 56 will move out of engagement with one of the contacts 52 into engagement with one of the contacts 54. This results in the energization of the electromagnet 53 with the resulting momentary energization of the windings of the electromagnetic device 71, and with the other attendant results described in connection with the energization of the electromagnet 53. Thus, it will be seen that the ratchet 77 and the temperature-adjusting cam 79 and the humidity-adjusting cam 80 are always moved through a predetermined angle in the same direction each time the electromagnetic device 71 is energized.

The contacts 52 and 54 are appropriately spaced in the ring 89. Preferably, the contacts 52 and 54 are uniformly spaced and the desired conditions of temperature and humidity throughout the drying operation are secured by appropriate design of the temperature-adjusting cam 79 and the humidity-adjusting cam 80. Different drying schedules may be obtained by the use of cams of appropriate different design. Where the drying schedule is determined by means of the cams 79 and 80, the scale arm 43 does not always have to start from the same position. The scale switch (52-54-56) can be set according to the moisture content of the representative sample by means of the weight 50, regardless of thickness or species.

While I have described and illustrated the invention as applied to a combined temperature and humidity controller in a single casing or instrument, it will be readily understood by those skilled in the art that the principles of the invention are equally applicable to a temperature controller alone.

or a humidity controller alone, or to an independent temperature controller employed in conjunction with an independent humidity controller. In such cases the temperature-adjusting cam would be attached to the temperature-controlling instrument and would be actuated in the manner described by the electromagnetic device 71; the humidity-adjusting cam would be attached to the humidity-controlling instrument and would be actuated by a similar electromagnetic device 71.

I claim:

1. The combination in a drying apparatus having temperature varying means and humidity varying means and controllers cooperating therewith for maintaining any desired conditions of temperature and humidity within the apparatus, of control means movable in response to the loss in weight of a representative sample of the material being dried as the drying operation progresses, a pair of electric relay windings adapted to be alternately energized by said control means, a movable member adapted to be actuated by the energization of each of said relay windings, an electromagnetic device, means for momentarily energizing said electromagnetic device each time said movable member is actuated, and means operated when said electromagnetic device is energized for adjusting said controllers to maintain predetermined different conditions of temperature and humidity within the drying apparatus as the drying operation progresses.

2. The combination in a drying apparatus having temperature varying means and a controller cooperating therewith for maintaining any desired condition of temperature within the apparatus, of control means movable in response to the loss in weight of a representative sample of the material being dried as the drying operation progresses, a pair of electric relay windings adapted to be alternately energized by said control means, a movable member adapted to be actuated by the energization of each of said relay windings, an electromagnetic device, means for momentarily energizing said electromagnetic device each time said movable member is actuated, and means operated when said electromagnetic device is energized for adjusting said controller to maintain predetermined different conditions of temperature within the drying apparatus as the drying operation progresses.

3. The combination in a drying apparatus having humidity varying means and a controller cooperating therewith for maintaining any desired condition of humidity within the apparatus, of control means movable in response to the loss in weight of a representative sample of the material being dried as the drying operation progresses, a pair

of electric relay windings adapted to be alternately energized by said control means, a movable member adapted to be actuated by the energization of each of said relay windings, an electromagnetic device, means for momentarily energizing said electromagnetic device each time said movable member is actuated, and means operated when said electromagnetic device is energized for adjusting said controller to maintain predetermined different conditions of humidity within the drying apparatus as the drying operation progresses.

4. In an apparatus for drying materials which require different conditions of temperature and humidity during the drying operation, temperature and humidity controllers having temperature-setting means cooperating with means for maintaining determined conditions of temperature within the apparatus and humidity-setting means cooperating with means for maintaining determined conditions of humidity within the apparatus, an electromagnetic device, a lever reciprocally moved by said electromagnetic device, a member adapted to be rotated in one direction a predetermined amount by each reciprocal movement of the lever, a temperature-adjusting cam secured to said member and operatively connected with the temperature-setting means, a humidity-adjusting cam secured to said member and operatively connected with the humidity-adjusting means, means for producing an action indicative of the loss of weight of a representative sample of the material being dried as the drying operation progresses, and means for actuating said electromagnetic device in response to said action.

5. In an apparatus for drying materials which require different conditions of temperature and humidity during the drying operation, temperature and humidity controllers having temperature-setting means cooperating with means for maintaining determined conditions of temperature within the apparatus and humidity-setting means cooperating with means for maintaining determined conditions of humidity within the apparatus, an electromagnetic device, a pivoted lever arranged to be reciprocated by the electromagnetic device, a rotatably mounted ratchet, a temperature-adjusting cam secured to the ratchet and operatively connected with the temperature-setting means, a humidity-adjusting cam secured to the ratchet and operatively connected with the humidity-setting means, a pawl on the lever adapted to engage and move the ratchet a predetermined amount in one direction each time the lever is reciprocated, means for producing an action indicative of the loss of weight of a representative sample of the material being dried as the drying

operation progresses, and means for actuating said electromagnetic device in response to said action.

6. In an apparatus for drying materials which require different conditions of temperature and humidity during the drying operation, temperature and humidity controllers having temperature-setting means cooperating with means for maintaining determined conditions of temperature within the apparatus and humidity-setting means cooperating with means for maintaining determined conditions of humidity within the apparatus, an electromagnetic device, means actuated by said electromagnetic device for adjusting said temperature-setting means and said humidity-setting means, means for producing an action indicative of the loss of weight of a representative sample of the material being dried as the drying operation progresses, a pair of electromagnets adapted to be energized alternately in response to said action, an electric circuit including said electromagnetic device, a stationary contact in said circuit, a movable element adapted to be reciprocated by the alternate energization of said electromagnets, and a contact on the movable element adapted to engage said stationary contact and close said electric circuit as the movable element is reciprocated.

7. In an apparatus for drying materials which require different conditions of temperature and humidity during the drying operation, temperature and humidity controllers having temperature-setting means cooperating with means for maintaining determined conditions of temperature within the apparatus and humidity-setting means cooperating with means for maintaining determined conditions of humidity within the apparatus, an electromagnetic device, a temperature-adjusting cam operatively associated with the temperature-setting means, a humidity-adjusting cam operatively associated with the humidity-setting means, said temperature-adjusting cam and said humidity-adjusting cam being actuated a predetermined prescribed amount in one direction each time said electromagnetic device is energized, means for producing an action indicative of the loss of weight of a representative sample of the material being dried as the drying operation progresses, a pair of electromagnets adapted to be energized alternately in response to said action, an electric circuit including said electromagnetic device, a stationary contact in the circuit, a movable element adapted to be reciprocated by the alternate energization of said electromagnets, and a contact on the movable element adapted to engage said stationary contact and close said electric circuit as the movable element is reciprocated.

8. In an apparatus for drying materials

which require different conditions of temperature and humidity during the drying operation, temperature and humidity controllers having temperature-setting means cooperating with means for maintaining determined conditions of temperature within the apparatus and humidity-setting means cooperating with means for maintaining determined conditions of humidity within the apparatus, an electromagnetic device, a rotatably mounted shaft, a lever loosely mounted on the shaft and arranged to be actuated by the electromagnetic device, a ratchet secured to the shaft, a temperature-adjusting cam secured to the shaft and operatively associated with the temperature-setting means, a humidity-adjusting cam secured to the shaft and operatively associated with the humidity-setting means, a pawl on the lever adapted to engage and move the ratchet a predetermined amount in one direction each time said electromagnetic device is energized, means for producing an action indicative of the loss of weight of a representative sample of the material being dried as the drying operation progresses, a pair of electromagnets adapted to be energized alternately in response to said action, an electric circuit including said electromagnetic device, a stationary contact in the circuit, a movable element adapted to be reciprocated by the alternate energization of said electromagnets, and a contact on the movable element adapted to engage said stationary contact and close said electric circuit as the movable element is reciprocated.

9. In an apparatus for drying materials which require different conditions of temperature and humidity during the drying operation, temperature and humidity controllers having temperature-setting means cooperating with means for maintaining determined conditions of temperature within the apparatus and humidity-setting means cooperating with means for maintaining determined conditions of humidity within the apparatus, an electromagnetic device, a rotatably mounted shaft, a lever loosely mounted on the shaft and arranged to be actuated by the electromagnetic device, a ratchet secured to the shaft, a temperature-adjusting cam secured to the shaft and operatively associated with the temperature-setting means, a humidity-adjusting cam secured to the shaft and operatively associated with the humidity-setting means, a pawl on the lever adapted to engage and move the ratchet a predetermined amount in one direction each time said electromagnetic device is energized, means for producing an action indicative of the loss of weight of a representative sample of the material being dried as the drying operation progresses, and means for periodically

energizing said electromagnetic device in response to said action.

10. In an apparatus for drying materials

which require different conditions of temperature during the drying operation, a temperature controller having temperature setting means cooperating with means for maintaining determined conditions of temperature within the apparatus, an electro-

10 magnetic device, a rotatably mounted shaft, a lever loosely mounted on the shaft and arranged to be actuated by the electromagnetic device, a ratchet secured to the shaft, a temperature-adjusting cam secured to the

15 shaft and operatively associated with said temperature-setting means, a pawl on the lever adapted to engage and move the ratchet a predetermined amount in one direction

20 each time said electromagnetic device is energized, means for producing an action indicative of the loss of weight of a representative sample of the material being dried as the drying operation progresses, and

25 means for causing said action to energize said electromagnetic device.

11. In an apparatus for drying materials which require different conditions of temperature during the drying operation, a tem-

30 perature controller having temperature-set-
ting means cooperating with means for maintaining determined conditions of tem-

35 perature within the apparatus, an electro-
magnetic device, means actuated by said

electromagnetic device for adjusting the temperature-setting means, means for pro-
ducing an action indicative of the loss of

40 weight of a representative sample of the material being dried as the drying operation progresses, a pair of electromagnets adapted to be energized alternately in re-

45 sponse to said action, an electric circuit in-
cluding said electromagnetic device, a sta-
tionary contact in the circuit, a movable

50 element adapted to be reciprocated by the alternate energization of said electromagnets, and a contact on the movable element adapted to engage said stationary contact and close said electric circuit as the movable element is reciprocated.

12. In an apparatus for drying materials which require different conditions of tem-
perature during the drying operation, a tem-

55 perature controller having temperature-set-
ting means cooperating with means for main-

60 taining determined conditions of tempera-
ture within the apparatus, an electro-
magnetic device, means actuated by said

65 electromagnetic device, for adjusting the temperature-setting means, means for pro-
ducing an action indicative of the loss of

70 weight of a representative sample of the ma-

terial being dried as the drying operation pro-

75 gresses, a pair of electromagnets adapted to be energized alternately in response to

80 said action, an electric circuit including said

3
said electromagnetic device is energized, means for producing an action indicative of the loss of weight of a representative sample of the material being dried as the drying operation progresses, and means for causing said action to energize said electromagnetic device.

16. In an apparatus for drying materials which require different conditions of humidity during the drying operation, a humidity controller having humidity-setting means cooperating with means for maintaining determined conditions of humidity within the apparatus, an electromagnetic device, means actuated by said electromagnetic device for adjusting the humidity-setting means, means for producing an action indicative of the loss of weight of a representative sample of the material being dried as the drying operation progresses, a pair of electromagnets adapted to be energized alternately in response to said action, an electric circuit including said electromagnetic device, a stationary contact in the circuit, a movable element adapted to be moved by each of said electromagnets, a contact on the movable element adapted to engage said stationary contact and close said electric circuit when the movable element is moved by either of said electromagnets, and means operated by said movable element for de-energizing that electromagnet causing movement of the movable element.
17. In an apparatus for drying materials which require different conditions of humidity during the drying operation, a humidity controller having humidity-setting means cooperating with means for maintaining determined conditions of humidity within the apparatus, an electromagnetic device, means actuated by said electromagnetic device for adjusting the humidity-setting means, means for producing an action indicative of the loss of weight of a representative sample of the material being dried as the drying operation progresses, and means for causing said action to energize said electromagnetic device.

18. In an apparatus for drying materials which require different conditions of humidity during the drying operation, a humidity controller having humidity-setting means cooperating with means for maintaining determined conditions of humidity within the apparatus, an electromagnetic device, a lever arranged to be reciprocally moved by said electromagnetic device, a rotatably mounted ratchet, a humidity-adjusting cam secured to said ratchet and operatively associated with the humidity-setting means, a pawl on the lever adapted to engage and move the ratchet a predetermined amount in one direction each time said electromagnetic device is energized, means for producing an action indicative of the loss of weight of a representative sample of the material being dried as the drying operation progresses, and means for causing said action to energize said electromagnetic device.

In testimony whereof I affix my signature.

JOHN BERCHMANS WELCH.
